UNITED STATES PATENT OFFICE

IRVING M. CRAFTS, OF GILDERSLEEVE, CONNECTICUT, ASSIGNOR TO THE PICKERING GOVERNOR COMPANY, OF PORTLAND, CONNECTICUT, A CORPORATION

GOVERNOR

Application filed March 28, 1930. Serial No. 439,601.

This invention relates to an improvement in governors and particularly to centrifugal governors. These governors include springs attached at one end to a sleeve fixed to a 5 spindle and at the other end to a collar longitudinally movable on said spindle, the weights being thrown outward by centrifugal force. In governors of this type, the weights are moved solely by the springs, which are 10 liable to torque, particularly when the speed changes. It is necessary that these springs should have considerable flexibility, and, to avoid torque, recourse has been made to using two or more springs for each weight.

15 The object of this invention is to provide a cage around said weights, to impart movement thereto and to prevent torque, and the invention consists in the construction as hereinafter described and particularly recited 20 in the claims.

In the accompanying drawings:

Fig. 1 is a front view, partly in section, of a governor constructed in accordance with my invention;

25 Fig. 2 is a side view of the same;

Fig. 3 is a sectional view on the line 3—3 of Fig. 1;

Fig. 4 is a sectional view on the line 4—4 of Fig. 2; and

30 Fig. 5 is a perspective view of the guide-cage, detached.

In illustrating my invention, I have shown it in connection with a governor forming the subject of an application filed February 3, 35 1930, Serial No. 425,562, but it will be understood that the invention is applicable to various types of governors.

The governor of the type shown includes 40 a spindle 10 and a sleeve 11 to which springs 12 and 13 are connected, the other ends of the springs being connected with a collar 14 loose on the spindle, the collar 14 being coupled with a controlling-mechanism. Connected with the springs are weights 15 and 16 and, 45 as shown, these weights have parallel side walls 17. These weights are arranged in a guide-cage 18 formed with a sleeve 19 which is fixed to the spindle 10 so as to turn therewith, and this cage includes two box-like 50 chambers 20 and 21 having parallel side walls

22 between which the weights 15 and 16 are arranged and in which they are free to move radially but held against torque. Preferably, the two chambers will also be connected by a centrally-arranged flange 23 for reinforcement. 55

As the spindle 10 is turned, the cage and weights are turned with it, and as the speed increases, the weights move outward so as to draw the collar 14 downward and through 60 suitable mechanism control the device for which it is used.

The cages move the weights, which are thus guided in their movement, both laterally and vertically, and the weights so closely fit the 65 chamber that they cannot be turned and hence prevent torque of the springs.

I claim:

1. In a governor, the combination with a 70 spindle, a sleeve fixed to the spindle, a collar movable on said spindle, springs connecting the sleeve and collar, weights mounted on said springs, and cages within which the said weights closely fit and may move radially but by which torque of the springs is 75 prevented.

2. In a governor, the combination with a 80 spindle, a sleeve fixed to the spindle, a collar movable on said spindle, springs connecting the sleeve and collar, weights mounted on said springs, and a guide-cage fixed to the spindle and including a separate chamber for each weight and in which weights closely fit, whereby torque of the springs is 85 prevented.

3. In a governor, the combination with a 90 spindle, a sleeve fixed to the spindle, a collar movable on said spindle, springs connecting the sleeve and collar, weights having parallel side walls and mounted on said springs, and a guide-cage secured to said spindle and formed with chambers having parallel side walls enclosing said weights.

4. In a governor, the combination with a 95 spindle, a sleeve fixed to the spindle, a collar movable on said spindle, springs connecting the sleeve and collar, weights having parallel side walls and mounted on said springs, and a guide-cage having two chambers arranged 100 on opposite sides of the spindle and formed

with chambers having parallel side walls enclosing said weights.

5. In a governor, the combination with a spindle, a sleeve fixed to the spindle, a collar movable on said spindle, springs connecting the sleeve and collar, weights mounted on said springs and having parallel side walls, and a guide-cage formed with a sleeve fixed to said spindle, cages on opposite sides of 10 said sleeve, said cages connected by a web, the said chambers having parallel side walls between which the said weights may move.

In testimony whereof, I have signed this specification.

15

IRVING M. CRAFTS.
